Patented Oct. 29, 1968

212,530

TRUCK BED GUARD

Wayne E. Smith, 312 S. Chestnut,
Lamoni, Iowa 50140

Filed Aug. 23, 1967, Ser. No. 8,351

Term of patent 14 years

(Cl. D14—6)

Fig. 1

Fig. 5 Fig. 6

Fig. 4

FIG. 1 is a rear perspective view of two of the truck bed guards mounted on a truck;

FIG. 2 is a top view of the truck bed guard;

FIG. 3 is a side view of the truck bed guard of FIG. 2;

FIG. 4 is a bottom view of the truck bed guard of FIG. 3;

FIG. 5 is an end view as seen along line 5—5 of FIG. 3; and

FIG. 6 is an end view as seen along line 6—6 of FIG. 3.

The truck shown in broken lines in FIG. 1 is included only for illustrative purposes.

I claim:

The ornamental design for a truck bed guard, substantially as shown and described.
